UNITED STATES PATENT OFFICE

ELBERON DOUGLAS SMITH, OF BROOKLYN, NEW YORK, ASSIGNOR TO AMERICAN MACHINE & FOUNDRY COMPANY, A CORPORATION OF NEW JERSEY

CIGARETTE FEED TOBACCO COMPRESSOR

Application filed August 20, 1931. Serial No. 558,370.

This invention relates to an improvement in tobacco feeds for continuous rod cigarette machines, its main object being to overcome the difficulties heretofore experienced in making a perfect cigarette rod by providing a tobacco feed compressor comprising means for compressing the tobacco showered from the feed chute of the tobacco feed to approximately the size or cross-section of the tobacco core in the finished cigarette rod, thereby facilitating the forming of the rod in the machine, and means for feeding the compressed tobacco to the travelling cigarette paper strip in the forward direction at a speed equal to that of the latter, thereby preventing skidding between tobacco and paper. With this and other objects not specifically mentioned in view, the invention consists in certain constructions and combinations hereinafter fully described and then specifically set forth in the claims hereunto appended.

Heretofore, the tobacco stream was fed from a feed chute directly upon the surface of the running paper strip, thereby striking the surface at right angles which, due to the inertia of the tobacco mass, caused a delay in its partaking of the motion of the paper with the result that, relative to the moving surface, the deposited tobacco moves backward for a short distance, thereby disturbing the evenness of the layer.

To overcome this inertia effect, the tobacco from the feed chute, by means of intermediate belts, is fed onto the paper strip with a forward speed equal to that of the strip so that there can be no relative motion between them. The tobacco from the feed chute is fed upon an inclined forwarding belt the rough surface of which prevents any skidding of tobacco. The latter is carried on this belt beneath a compressor belt moving at the same speed and in the same direction of the first belt and forming with the same a tapered space leading to the moving paper strip. The narrowing of the space so formed causes gradual compression of the tobacco stream to approximately its final size, thereby producing a uniform and homogeneous tobacco core and taking a corresponding amount of compression work off the rod former which folds

the passing strip around the tobacco layer to form the cigarette rod, this relieving of the rod former being of great importance in high speed machines. The thus compressed stream of tobacco is fed onto the running paper strip at the same speed and in the direction of the latter and thus partakes of its motion immediately.

In the accompanying drawing in which like characters of reference indicate the same or like parts:

Fig. 1 is a front elevation of the tobacco feed compressor with the front cover removed;

Fig. 2 is a sectional end elevation of the same, taken on line 2—2 of Fig. 1;

Fig. 3 is a sectional end elevation taken on line 3—3 of Fig. 1; and

Fig. 4 is a sectional top view taken on line 4—4 of Fig. 3, showing the compressed tobacco mass leaving the compressor and entering into the receiving tongue of the rod former.

In carrying the invention into effect there is provided a cigarette machine feed chute, means for continuously forwarding a cigarette paper strip, and mechanism under the bottom of said chute for angularly intercepting the tobacco showered therefrom and compressing it to the approximate cross-section of the core of a cigarette rod and forwarding and delivering the compressed tobacco to the cigarette paper strip at an angle thereto. In the best forms of construction contemplated said mechanism includes a travelling tobacco forwarding belt having its upper run arranged to angularly intercept the tobacco falling through the feed chute, and a compressor belt operating to compress the tobacco on the upper run of said forwarding belt and travelling therewith to deliver the compressed tobacco to the cigarette paper strip at an angle thereto. These various means and parts may be widely varied within the scope of the claims for the particular device selected to illustrate the invention is but one of many possible concrete embodiments of the same. The invention therefore is not to be restricted to the specific construction shown and described.

Referring to Fig. 1, the cigarette feed tobacco compressor is mounted on a frame 5 forming part of the main frame of the cigarette machine and carrying the pulleys 6 and 7 mounted on shafts 8 and 9, respectively, which are driven in opposite directions, shown by arrows, from the main drive of the machine. Pulley 6 drives a comparatively short compressor belt 10 over idler rollers 11, 12 and 13 and belt tightener 14 which are supported from the frame 5. Pulley 7 drives a long forwarding belt 15, extending along substantially the entire length of the feed chute, over idler rollers 16, 17 and belt tightener 18 which are also supported from the frame 5. Between the idler rollers 11 and 12, and 16 and 17, respectively, the travelling belts 10 and 15 run in the same direction forming between them a tapered pathway or space for compressing the tobacco stream T delivered upon the upper runs of belts 10 and 15 from a feed chute 19 which confines the tobacco falling therethrough in a shower. The tobacco is guided on its way to the belts 10 and 15 by a rear wall 20 fixed on the frame 5 and a removable front cover 21 pivoted on said frame, Fig. 2, while the lower part of the compressor is equipped with tobacco side guides 22 and 23, Fig. 3. Since the guide 22 is secured to the frame 5 and connected to guide 23 by the shaft of the roller 13, the guide 23 is also supported from the guide 22. The tobacco is gradually compressed between the lower run of the belt 10 and the upper run of the belt 15 to approximately the cross-section of the core of the finished cigarette, thus leaving the rod former of the machine free to perform only the final shaping of the cigarette rod.

The cigarette paper strip P is continuously fed from a reel R over a guide roller 24, supporting plate 25, and a laterally adjustable paper guide 26 onto an endless traction tape 27 driven from the main drive of the machine and running over a small roller 28 placed on a level with supporting plate 25. To provide for adjustment of the paper guide 26 it is mounted on a screw threaded into a bracket fixed on the frame 5 and underlying the lower run of the belt 15 behind the roller 28, whereby the cigarette paper strip may be laterally adjusted without stopping the machine, as shown in Figs. 2 and 3. The belts 10 and 15 and the tape 27 are driven at a predetermined velocity so that the compressed tobacco stream T and the paper strip P have the same speed when coming together and when entering the tongue 28a of the rod former. In order to press the tobacco on the cigarette paper strip to prevent any tobacco from following the belt 10 when it leaves the tobacco stream T at roller 13, a thin guide plate 29 extending into tongue 28a is fastened to guide 22. Plate 29 is cut at an angle 30 to prevent any tobacco which

may project upwardly from being arrested thereby, the tobacco following the angle 30 and passing between plate 29 and guide 23 into the rod former. Furthermore, the tongue extends sufficiently to engage the portion of belt 10 running over roller 13 to scrape off any tobacco which may adhere to the belt. The compressor is equipped with supporting plates 31, 32 and 33 for belt 10, and with supporting plates 34 and 35 for belt 15. These supporting plates are fixed to the frame 5 in position to properly support the respective runs of belts 10 and 15. To prevent any tobacco or dust from accumulating upon the surfaces of pulleys 6 and 7 or of rollers 11, 12, 13, 14, 16, 17 and 18, each of the same is equipped with a scraper plate 36.

In view of the foregoing a detailed description of the operation of the device is deemed unnecessary and omitted in the interest of brevity.

What is claimed is:

1. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including a traveling forwarding belt having an inclined upper run arranged to angularly intercept a portion of the shower of tobacco and feed it to said cigarette paper strip, and a traveling compressor belt having an inclined upper run arranged to angularly intercept the remaining portion of said shower and feed it onto the layer of tobacco on said forwarding belt delivered directly from said shower, said compressor belt having another run arranged at an angle to its upper run to compress the tobacco on said forwarding belt to the approximate cross-section of the core of a cigarette rod.

2. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism operating to feed the compressed tobacco to the cigarette paper strip at a speed substantially equal to the speed of the cigarette paper strip and including a traveling forwarding belt having its upper run arranged to angularly intercept a portion of the shower of tobacco at an acute angle, and

5 a compressor belt having its upper run arranged at an obtuse angle to the upper run of said forwarding belt to angularly intercept the remaining portion of said shower and feed it onto the layer of tobacco on the upper run of said forwarding belt delivered directly from said shower.

3. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including travelling belts having their upper 20 runs oppositely inclined at an obtuse angle to each other and underlying the bottom of said chute to intercept the falling tobacco at an acute angle.

4. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including a travelling forwarding belt underlying the bottom of said chute and angularly intercepting the falling tobacco, and a compressor belt arranged to compress the tobacco on said forwarding belt to the approximate cross-section of the core of a cigarette rod and cooperate with said forwarding belt to feed the compressed tobacco directly to the cigarette paper strip, and then press the compressed tobacco on said cigarette paper strip.

5. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including a travelling forwarding belt having its upper run arranged to angularly intercept a portion of the shower of tobacco, and a compressing belt arranged to angularly intercept another portion of said shower and feed it to the tobacco on said forwarding belt, and cooperate with said forwarding belt to compress the tobacco and deliver it to the

cigarette paper strip, and then press the compressed tobacco on said strip.

6. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including a travelling forwarding belt arranged to angularly intercept the falling tobacco, and a compressor belt having a run overlying said forwarding belt and adapted to compress the tobacco thereon and cooperating therewith to feed the compressed tobacco directly to the cigarette paper strip, and having a horizontal run adapted to press the compressed tobacco on said strip.

7. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said mechanism including a travelling forwarding belt arranged to angularly intercept the falling tobacco and forward it to the cigarette paper strip, an endless travelling compressor belt having a horizontal run adapted to press the tobacco on the cigarette paper strip, and side guides for the tobacco delivered to the cigarette paper strip adapted to guide the tobacco passing under the horizontal run of said compressor belt.

8. The combination with a cigarette machine feed chute adapted to confine the tobacco falling therethrough in a shower, of means for continuously forwarding a cigarette paper strip, and mechanism under the bottom of said chute for angularly intercepting the falling tobacco and compressing it to the approximate cross-section of the core of a cigarette rod and forwarding and delivering the compressed tobacco to the cigarette paper strip at an angle thereto, said means including side guides for the tobacco on said strip, a laterally adjustable guide for the cigarette paper strip, and an endless traction tape for forwarding the strip under said mechanism, said guide being arranged to engage the cigarette paper strip before it reaches said tape, whereby the strip may be laterally adjusted without stopping the machine.

9. The combination with means for continuously forwarding a cigarette paper strip,

of mechanism for forwarding a stream of tobacco and compressing it to the approximate cross-section of the core of a cigarette rod and delivering the compressed tobacco to the cigarette paper strip at an angle thereto at a speed substantially equal to that of the strip, said mechanism including a forwarding belt, and a compressor belt, said compressor belt having a horizontal run adapted to press the tobacco on the cigarette paper strip.

10. The combination with means for continuously forwarding a cigarette paper strip, of mechanism for forwarding a stream of tobacco and compressing it to the approximate cross-section of the core of a cigarette rod and delivering the compressed tobacco to the cigarette paper strip at an angle thereto at a speed substantially equal to that of the strip, said mechanism including an inclined 15 tobacco forwarding belt, a travelling compressor belt arranged to compress the tobacco on said forwarding belt, said compressor belt having a horizontal run adapted to press the tobacco on said cigarette paper strip, side 20 guides for the tobacco delivered to the cigarette paper strip, and a plate adapted to press the tobacco on the strip between said side guides.

11. Means for forwarding a stream of tobacco and compressing it to the approximate cross-section of the core of a cigarette rod, comprising a forwarding belt having its upper run inclined from the vertical, a compressor belt having its lower run arranged 25 adjacent said upper run to compress the tobacco thereon, the upper run of said compressor belt being arranged at an angle to its lower run and adapted to feed tobacco to the upper run of said forwarding belt, and a rear wall and a front cover for guiding the tobacco into the space between said runs.

12. The combination with a cigarette machine feed chute adapted to confine tobacco falling therethrough in a shower, of a rod former having a tongue, an endless traction tape for forwarding a cigarette paper strip through said rod former, mechanism under the bottom of said chute for angularly intercepting the falling tobacco and compressing it to the approximate cross-section of the core of a cigarette rod and forwarding and delivering the compressed tobacco to the cigarette paper strip on said tape at an acute angle thereto, and a guide plate extending 30 under said tongue and arranged to engage the tobacco on the cigarette paper strip on said tape to guide it under said tongue.

13. The combination with a cigarette machine feed chute adapted to confine tobacco falling therethrough in a shower, of a rod former having a tongue, an endless traction tape for forwarding a cigarette paper strip through said rod former, mechanism under the bottom of said chute for angularly intercepting the falling tobacco and compress-

ing it to the approximate cross-section of the core of a cigarette rod and forwarding and delivering the compressed tobacco to the cigarette paper strip on said tape at an acute angle thereto, and a guide plate extending under said tongue and arranged to engage the tobacco on the cigarette paper strip on said tape to guide it under said tongue, said mechanism including a forwarding belt having an inclined upper run arranged to angularly intercept a portion of the shower of tobacco and feed it to said cigarette paper strip, and a compressor belt having an inclined upper run arranged to angularly intercept the remaining portion of said shower and feed it onto the layer of tobacco on said forwarding belt delivered from said shower, the lower run of said compressor belt being arranged to compress the tobacco on said forwarding belt to the approximate cross-section of the core of the cigarette rod.

14. The combination with a cigarette machine feed chute adapted to confine tobacco falling therethrough in a shower, of a rod former having a tongue, an endless traction tape for forwarding a cigarette paper strip through said rod former, mechanism under the bottom of said chute for angularly intercepting the falling tobacco and compressing it to the approximate cross-section of the core of a cigarette rod and forwarding and delivering the compressed tobacco to the cigarette paper strip on said tape at an acute angle thereto, and a guide plate extending under said tongue and arranged to engage the tobacco on the cigarette paper strip on said tape to guide it under said tongue, said mechanism including a forwarding belt and a compressor belt extending over the traction tape beyond the delivery end of said forwarding belt to maintain the tobacco on the cigarette paper strip on said tape in compressed condition.

15. The combination with a cigarette machine feed chute adapted to confine tobacco falling therethrough in a shower, of a rod former having a tongue, an endless traction tape for forwarding a cigarette paper strip through said rod former, mechanism under the bottom of said chute for angularly intercepting the falling tobacco and compressing it to the approximate cross-section of the core of a cigarette rod and forwarding and delivering the compressed tobacco to the cigarette paper strip on said tape at an acute angle thereto, and a guide plate extending under said tongue and arranged to engage the tobacco on the cigarette paper strip on said tape to guide it under said tongue, one edge of said guide plate being cut at an angle to prevent obstruction of any tobacco which may project upwardly from the cigarette paper strip.

16. In a cigarette machine for forming freely falling showered tobacco into a continuous

rod, the combination with a conveyor arranged to carry tobacco resting thereon by gravity said conveyor comprising a travelling web having at least a portion of its carrying 5 surface inclined to the horizontal, of a chute having a capacity sufficient to permit a free falling of the showered tobacco and acting to guide the tobacco onto said inclined carrying surface, mechanism for forwarding the 10 tobacco stream formed on the web to the rod forming means, and a belt compressor for compressing the tobacco stream.

17. In a cigarette machine for forming freely falling showered tobacco into a continuous 15 rod, the combination with a travelling web having at least a portion of its carrying surface inclined to the horizontal, of a chute acting to guide the tobacco onto said inclined carrying surface, mechanism for forwarding the 20 tobacco stream formed on the web to the rod forming means, and a belt compressor for compressing the tobacco stream, said tobacco compressing belt having a run parallel to the axis of the cigarette rod acting on the upper 25 side of the tobacco stream.

18. In a cigarette machine for forming freely falling showered tobacco into a continuous rod, the combination with a travelling web having at least a portion of its carrying 30 surface inclined to the horizontal, of a chute acting to guide the tobacco onto said inclined carrying surface, mechanism for forwarding the tobacco stream formed on the web to the rod forming means, a belt compressor for compressing 35 the tobacco stream, said belt compressor having a horizontal run compressing the stream of tobacco.

19. In a cigarette machine for forming freely falling showered tobacco into a continuous 40 rod, the combination with a conveyor arranged to carry tobacco resting thereon by gravity said conveyor comprising a travelling web having at least a portion of its carrying surface inclined to the horizontal, of a chute 45 having a capacity sufficient to permit a free falling of the showered tobacco and acting to guide the tobacco onto said inclined carrying surface, mechanism for forwarding the tobacco stream formed on the web to the rod forming 50 means, and a belt compressor for compressing the tobacco stream, said belt compressor cooperating with the inclined portion of the web.

20. In a cigarette machine for forming freely falling showered tobacco into a continuous 55 rod, the combination with a conveyor comprising a travelling web having at least a portion of its carrying surface inclined to the horizontal, of a chute acting to guide the tobacco onto said inclined carrying surface, mechanism for forwarding the tobacco stream formed on the web to the rod forming means, and a belt compressor for compressing the tobacco stream, said chute comprising spaced 60 plates overlying and extending along the web

with their lower edges in engagement with the upper marginal portions of the web.

21. In a cigarette machine for forming freely falling showered tobacco into a continuous 70 rod, the combination with a rod former tongue, of a travelling web having its end a substantial distance back of the tongue, a chute acting to guide the tobacco onto said web, mechanism for forwarding the tobacco stream formed on the web to the rod forming 75 means, and a belt compressor for compressing the tobacco stream, said tobacco compressing belt having an operating run extending from a position in close proximity to the end of the inclined portion of said web to a position in 80 close proximity to said tongue.

22. In a cigarette machine for forming freely falling showered tobacco into a continuous rod, the combination with rod forming means, of a travelling web, a chute acting to guide the 85 tobacco onto said web, mechanism for forwarding the tobacco stream formed on the web to the rod forming means, and a belt compressor for compressing the tobacco stream, said rod forming means including a tongue 90 having a portion close to the web acting as a scraper on the compressor belt.

23. In a cigarette machine for forming freely falling showered tobacco into a continuous rod, the combination with a travelling web having at least a portion of its carrying surface inclined to the horizontal, of a chute acting to guide the tobacco onto said inclined carrying surface, mechanism for forwarding the tobacco stream formed on the 95 web to the rod forming means, and a belt compressor for compressing the tobacco stream, said compressor belt coacting on the lower portion only of said web to compress tobacco thereon without preventing free falling of tobacco on the upper portion of said web.

24. In a cigarette machine for forming freely falling showered tobacco into a continuous rod, the combination with a conveyor 110 arranged to carry tobacco resting thereon by gravity, said conveyor comprising a travelling web having at least a portion of its carrying surface inclined with respect to the horizontal, of a chute having a capacity sufficient 115 to permit free falling of the showered tobacco and acting to guide the tobacco onto said inclined carrying surface, and means for guiding said web in transversely flat condition.

25. In a cigarette machine for forming freely falling showered tobacco into a continuous rod, the combination with a conveyor arranged to carry tobacco resting thereon by gravity, said conveyor comprising a travelling web having at least a portion of its carrying surface inclined with respect to the horizontal, of a chute having a capacity sufficient 125 to permit free falling of the showered tobacco and acting to guide the tobacco onto said 130

inclined carrying surface, means for guiding said web in transversely flat condition, and mechanism coacting with the marginal portions of said web to retain all the tobacco 5 received thereby on said web.

26. In a cigarette machine for forming freely falling showered tobacco into a continuous rod, the combination with a conveyor arranged to carry tobacco resting thereon by 10 gravity, said conveyor comprising a traveling web having at least a portion of its carrying surface inclined with respect to the horizontal, of a chute having a capacity sufficient to permit free falling of the showered 15 tobacco and acting to guide the tobacco onto said inclined carrying surface, and means for guiding said web in transversely flat condition, said chute having lower edge portions in engagement with the marginal portion of 20 the web.

27. In a cigarette machine, the combination with chute means for guiding showered tobacco, said chute means having opposed substantially parallel wall portions for forming 25 the showered tobacco into a sheet having substantially parallel sides, an inclined conveyor extending along the lower side of said sheet to form said tobacco into a narrow stream, and a belt compressor for compressing 30 said stream.

28. In a cigarette machine, the combination with a travelling web, of means for guiding showered tobacco onto said web, a traveling web overlying the first mentioned web 35 and coacting therewith to compress the tobacco resting thereon, and means entering between the edge of said webs and cooperating with the marginal portions thereof to retain the tobacco on the mid-portion of the 40 web.

In testimony whereof, I have signed my name to this specification.

ELBERON DOUGLAS SMITH.
